ABSTRACT

In a urea dewaxing process, a powdery adduct, capable of being effectively separated by centrifuging, is formed at a temperature range of from about 20° to 40°C. if particular oil solvent mixtures are employed. Useful solvent mixtures are a C₅—C₆ hydrocarbon such as isopentane, hexane or benzene plus a higher boiling organic compound such as methylisobutylketone.

PROCESS FOR THE PRODUCTION OF NORMAL PARAFFINS BY UREA DEWAXING OF MINERAL OIL DISTILLATES

BACKGROUND OF THE INVENTION

This invention relates to the removal of normal paraffins from mineral oil distillates by a process known as urea dewaxing.

It is known to react the n-paraffins components of liquid hydrocarbon mixtures, such as mineral oil distillates, with urea to form solid adducts. These adducts are separated from the mineral oil filtrate by filtration, centrifugation, etc., washed with a solvent for hydrocarbons and, finally, decomposed under the influence of heat, water and/or solvents, thereby recovering the urea and obtaining an n-paraffin product which still contains a minor amount of isoparaffins and other constituents, depending on the mineral oil distillate used and the operating conditions employed. A second product obtained from the mineral oil filtrate by way of this so-called urea dewaxing process is a hydrocarbon mixture which, as a result of the reduced n-paraffin content, has a lower pour point than the charge material.

This urea dewaxing process may be carried out with crystalline urea, advantageously admixed with minor amounts of such materials as water and methanol as an activator. However, aqueous or alcoholic urea solutions may also be used in this process. The adduct formation is normally carried out at a temperature of from about 20° to 40°C, using aqueous urea solutions saturated at an elevated temperature, for example, about 70°C.

It is also known that the selectivity of the urea dewaxing process may be improved by diluting the mineral oil distillate with oil solvents. Suitable oil solvents include low molecular weight alcohols and ketones, low boiling hydrocarbons such as butane, pentane, isopentane, hexane, and the like, and halogenated hydrocarbons such as dichloromethane.

German patent no. 1,098,657 discloses a process by which the n-paraffin-urea adduct is obtained as a dust-like powder having a medium particle size of or below about 0.1 mm, in the form of fine to coarse particles or as a very viscous aqueous slurry. The form of the adduct depends, among other factors, on the type of urea solvent used, if one is used, as well as on the concentration and amount of the urea solution; further, on the type of oil solvent used for diluting the mineral oil and, last but not least, on the adduct-forming temperature. Upon decomposition, the dust-like adduct, hereinafter called "powder adduct," yields a very pure n-paraffin. However, this powder adduct cannot be separated from the mineral oil filtrate by screening. On the other hand, although a coarse-grained adduct is readily siftable, it cannot be purified sufficiently by washing with the oil solvent and so the coarse-grained adduct yields a paraffin product with lower n-paraffin content. German patent no. 1,105,090 discloses a process wherein in a first stage a coarse-grained adduct is produced, and in a second stage this adduct is stirred with a suitable oil solvent and cooled to form powder adduct. The second stage employs what is termed a repulping operation.

German patent no. 1,098,657 discloses the influence of the adduct-forming temperature on the form of the adduct; powder adduct is stable only below a defined

temperature limit depending, among other factors, on the type of oil solvent used. If, for example, 100 parts by volume of a mineral oil boiling in the range of from 307 to 415°C are reacted with 100 parts by volume of aqueous urea solution saturated at 70°C., 300 parts by volume of dichloromethane (DCM) as oil solvent, powder adduct is obtained if the adduct-forming temperature is below 27°C.

If, instead of DCM, hexane or isopentane is used in the same parts by volume, a temperature of below 8°C is required to obtain powder adduct. If these solvents are replaced by such solvents as methanol, ethanol, acetone, butanone, methyl formate or methyl acetate, a sticky, nonpumpable adduct is formed when the temperature ranges between 20° and 35°C. Powder adduct is obtained only at substantially lower temperatures than with DCM or C₅-C₆ hydrocarbons. When higher boiling polar materials such as methylisobutylketone, butyl acetate, hexanol, or the like are used as solvents in adduct formation, very viscous emulsions are obtained which can be neither pumped nor filtered. Although all these solvents permitted production of powder adduct at very low adduct-forming temperatures, this mode of operation is not economically feasible because of the high cooling costs. While it is possible to produce adduct with DCM as the solvent in a desirable temperature of about 20 to 40°C, the continuous separation of the powder adduct from the liquid mixture by centrifuging is almost impossible because of the small difference in density between the DCM solution and the powder adduct.

It is an object of this invention to provide a process for the recovery of n-paraffins from mineral oil distillates whereby a powdery adduct is formed at a commercially attractive temperature through use of a solvent which also permits the effective separation of the adduct from the solvent-mineral oil mixture by means of centrifuging.

SUMMARY OF THE INVENTION

An adduct in powdery form is formed in a urea dewaxing process at a temperature range of about 20 to 40°C. by admixing with the n-paraffin-containing mineral oil distillate an organic solvent of 70 to 95 volume percent of a C₅-C₆ hydrocarbon and 30 to 5 percent of a higher boiling organic compound such as methylisobutylketone. The solvent combination has the concomitant advantage of permitting the effective separation of the powdery adduct from the distillate-solvent mixture by centrifuging.

DESCRIPTION OF THE PREFERRED EMBODIMENTS

We have found that powder adduct is obtained in a urea dewaxing process at an economically and commercially attractive temperature range of from about 20° to 40°C., if 70 to 95 volume percent of a C₅-C₆ hydrocarbon such as isopentane, hexane or benzene and about 5 to 30 volume percent of methylisobutylketone are used as solvents. It has further been found that the separation of the powder adduct obtained from the mineral oil filtrate and from the solvent mixture used for washing can be effected surprisingly well by centrifugation. In view of German patent no. 1,105,090 this result was unexpected, since the solvent mixture has a lower specific gravity than the powder adduct. Accordingly, the separation of the powder adduct from the

mineral oil raffinate (primary filtrate), the washing of the adduct with liquid solvent, and also the treatment of the washed adduct, particularly with vaporous solvent, can be effected in a commercial separator such as a full jacket centrifuge.

The present invention, therefore, relates to improvements in a process for the recovery of n-paraffins from mineral oil distillates comprising reacting the mineral oil, diluted with an organic solvent, with an aqueous or alcoholic urea solution saturated at elevated temperature to form solid n-paraffin-urea adducts, separating the adducts from the dewaxed mineral oil solution, washing the adducts with an organic solvent and decomposing the washed adducts by organic solvent extraction or by the influence of heat, water and/or said organic solvent. The specific improvements of this invention are directed to diluting the mineral oil distillate charge material with a solvent mixture of from about 95 to 70 volume percent of hydrocarbons having from about 5 to 6 carbon atoms and of from about 5 to 30 vol. percent of a higher boiling organic compound such as, methylisobutylketone (MIBK). It has further been found that mixtures of from about 95 to 70, particularly about 90 to 80, volume percent of aliphatic, cycloaliphatic or aromatic C₅-C₆ hydrocarbons, for example, isopentane, hexane or benzene, and from about 5 to 30, preferably about 10 to 20, volume percent of MIBK, used as oil solvents for the production of n-paraffin-urea adducts, are not only capable of raising the temperature limits for powder adduct formation to the commercially attractive temperature range of about 20° to 40°C, but they are also excellent wash agents, so efficient in freeing powder adduct and also fine-grained to coarse-grained n-paraffin-urea adducts from isoparaffins and other constituents by washing, reprecipitation and the like, that very pure normal paraffins are obtained upon decomposition of the adducts having been treated therewith.

Oil solvent mixtures consisting of from 95 to 70 volume percent of C₅ or C₆ hydrocarbons and from 5 to 30 volume percent of MIBK, are also suited to modify the so-called "repulping process" known from German patent no. 1,105,090 so as to produce powder adduct at the economically feasible temperature range employed in the first stage. This powder adduct can then be washed (with the same fresh oil solvent mixture) and, finally, dispersed ("repulped") therein with stirring. As distinct from the procedure disclosed in German patent no. 1,105,090, this dispersion can be heated to a temperature substantially above the adduct-forming temperature, without thereby causing the adduct to conglomerate or cake. If these dispersions are, subsequently, recooled to the original adduct-forming temperature, very pure n-paraffins in fairly high yields are obtained from the adduct.

Therefore, a particularly advantageous and preferred embodiment of the process of the invention is to conduct the reaction at a temperature of between about 20° and 40°C and prepare n-paraffin-urea powder adduct having an average particle size of about 0.1 mm or less.

This invention is further illustrated by the following examples.

EXAMPLE I

10 A light gas oil boiling in the range of from about 210° to 315°C (corresponding to a carbon number in the range of about 12 to 22) and containing about 16 wt. percent of n-paraffins was used. 100 parts by volume of this gas oil were diluted with 220 parts by volume of a solvent or solvent mixture and then reacted, while stirring, with 60 parts by volume of an aqueous urea solution, saturated at 70°C., to form a solid adduct.

15 Preliminary test runs were carried out under these conditions to determine the upper temperature limit for formation of the adduct in powder form (with an average particle size of about 0.1 mm or less). The adduct formation was conducted up to or close to this upper temperature limit. The powder adduct obtained 20 was separated from the liquid by filtration. Then, it was washed at adduct-forming temperature, using the same type and same amount of solvent or solvent mixture employed in the adduct-forming step. Finally, the powder adduct, washed and largely freed of the wash agent, 25 was decomposed under addition of hot water. The results are set forth in Table I below. The expression "n-paraffin yield" in the Table designates the content by weight of n-paraffins, based on charge material, obtained upon decomposition of the powder adduct. The 30 expression "purity of n-paraffin" designates the proportion of n-paraffins in the decomposition product.

35 In comparative Runs 1 to 4, the gas oil was diluted with hexane, benzene, isopentane or methylisobutylketone (MIBK). In Runs 1 to 3, powder adduct was formed only up to the upper temperature limit indicated in Table I. At higher adduct-forming temperatures, a coarse-grained or greasy, sticky adduct slurry was obtained. When MIBK was used as diluent (Run 4), a non-filtrable adduct gel was formed, both at room 40 temperature and at lower temperatures. For this reason, the n-paraffin yield and purity could not be determined.

45 In Runs 5 to 8, the first solvent, i.e., hexane (Runs 5 and 6) or benzene (Runs 7 and 8), was admixed with MIBK in amounts of about 5 and 10 volume percent (based on said first solvent), respectively. As shown in Table I, the temperature limits for the formation of the desired adduct were thereby raised quite considerably. Furthermore, there was a distinct increase in yield and 50 purity of the n-paraffins obtained as compared with comparative Runs 1 to 3.

EXAMPLE II

A "spindle oil O" boiling in the range of from about 317 to 420°C (corresponding to a carbon number range of between about 14 and 28) and containing about 16 wt. percent of n-paraffins was used. 100 parts by volume of said spindle oil were diluted with 200 parts by volume of an oil solvent or solvent mixture and reacted at temperatures of 20 or 35°C with 50 parts by volume of an aqueous urea solution, saturated at 70°C. The results are set forth in Table II below.

Comparative Runs 9, 10 and 13 were conducted with pure hexane as solvent and with an adduct-forming temperature of 20°C. A fine-grained adduct (average particle size 0.1 to 0.3 mm) resulted. In comparative Runs 15, 16 and 19 an adduct having a particle size of from about 0.3 to 0.6 mm was formed at 35°C. Powder adduct (average particle size about 0.1 or less) was obtained only at a temperature of 8°C or lower. At higher adduct-forming temperatures, and with hexane as solvent, a sticky adduct was obtained, which showed no further reaction.

In Runs 11, 12, 14, 17, 18 and 20, MIBK was substituted for about 5 volume percent of said hexane. By doing this and maintaining the other conditions, the av-

erage particle size of the adduct was reduced to 0.1 mm or less. The n-paraffins obtained from the runs using MIBK as a diluent component were of greater purity than those obtained in the comparative runs using hexane.

- 35 In Runs 10 and 16, MIBK was added only to the solvent used for washing the adduct. This raised the purity of the recovered paraffin by about 5 to 6 percent over comparative Runs 9 and 15.
- 40 In Runs 13, 14, 19, and 20, the washed adduct was "repulped" according to German Patent No. 1,105,090, with and without addition of MIBK. Here, the adduct, washed and largely freed of wash agent, was mixed with 200 parts by volume (based on original spindle oil charge) of the oil solvent or solvent mixture, stirred at the adduct-forming temperature employed for 5 min, filtered and again washed with the same amount of the same fresh solvent or solvent mixture. As the increase in purity of the recovered n-paraffins 45 shows the addition of MIBK was also advantageous in this "repulping treatment."
- 50 The data of Runs 9 to 20 are summarized in the following Table II.

We claim:

1. In a process for the recovery of n-paraffins from mineral oil distillates comprising reacting the mineral oil, diluted with an organic solvent, at a temperature of 20° to 40°C, with an aqueous or alcoholic urea solution saturated at elevated temperature to form solid n-paraffin-urea adducts, separating the adducts from the dewaxed mineral oil solution, washing the adducts with an organic solvent and decomposing the washed adducts by organic solvent extraction or by the influence of heat, water and/or said organic solvent, the improvement which comprises diluting the mineral oil distillate charge material in the adduct-forming step with an organic solvent which is a solvent mixture consisting essentially of from about 70 to 95 volume percent of a C₅-C₆ hydrocarbon and of from about 30 to 5 volume percent of methylisobutylketone.

35 2. A process according to claim 1 wherein the volume percent of C₅-C₆ hydrocarbon is 80 to 90 volume percent and the volume percent of the methylisobutylketone is 20 to 10 volume percent.

3. A process according to claim 1 wherein the C₅-C₆ 40 is isopentane.

4. A process according to claim 1 wherein the C₅-C₆ hydrocarbon is hexane.

5. A process according to claim 1 wherein the C₅-C₆ 45 hydrocarbon is benzene.

6. A process according to claim 1 wherein a powdery adduct having an average particle size of 0.1 mm. or less is formed in the adduct forming step.

7. A process according to claim 1 wherein the solvent 50 mixture is employed as the organic solvent to wash the adduct and to decompose the adduct.
